UNITED STATES PATENT OFFICE.

JEAN AUBÉ, OF PARIS, FRANCE.

PULVERIZING APPARATUS.

Application filed August 14, 1919. Serial No. 317,518.

To all whom it may concern:

Be it known that I, JEAN AUBÉ, a citizen of the Republic of France, and residing at Paris, Seine Department, No. 63 Avenue des Champs Elysées, in the Republic of France, have invented certain new and useful Improvements in or Relating to Pulverizing Apparatus, of which the following is a specification.

10 The present invention has for its object a pulverizing apparatus which effects an economy of motive power, and is arranged so as to be easily dismantled and inspected.

This result is obtained by utilizing a turbine in such a way as to cause the air which has carried away the dust to return to the apparatus, after it has been freed therefrom, and by evacuating the pulverized products through the upper part of the apparatus by 20 means of a circulating trunk communicating with the interior through openings which are adjustable in any manner.

The accompanying drawings represent by way of example a constructional form of the 25 invention.

Figure 1 is a vertical section thereof.

Figure 2 is a horizontal section, and,

Figure 3 is a plan view.

A central shaft 1 carries a turbine 2 and 30 a number of arms 3 to which are hung by joints the spindles of rollers 4, which are loose upon these spindles. The shaft 1 has a rotary motion imparted to it by means of driving pinions 5 and 6. The material to be 35 pulverized is introduced into the casing of the apparatus through a distributor 11 of any system; it falls between the circular base 12 of the pulverizer and the rollers 4 which, under the influence of centrifugal force, bear 40 strongly against the walls of this base.

A fan of any kind draws air constantly in a circulating trunk 7 placed at the upper part of the pulverizer, and communicates with the centre thereof by a number of openings 8 provided with adjustable dampers 9. The blast pipe 13 of this fan opens into the base of the pulverizer, below the turbine 2. In this pipe is interposed a dust separator (not shown) of any system.

50 The current of air loaded with dust which rises through the pulverizing apparatus is evacuated through the adjustable openings 8, and forced back by the fan into the pulverizer, then the air freed from dust returns to 55 the base of the pulverizer, whence it is

distributed to the interior by the turbine 2 the blades of which are preferably directed in such a way that the air passes without any shock.

14 denotes scoops rotating with the rollers 80 and with the turbine and serving to project the materials towards the grinding zone.

The adjustment of the position of the dampers 9 permits, by causing the depression 65 of the gaseous current to vary, the obtaining at pleasure of such fineness of the products as may be desired, and the suction through the periphery of the pulverizer into the circulating trunk 7 permits complete freeing 70 of the upper part of the apparatus which makes cleaning and inspection more easy.

The utilization of the turbine 2 to assist the reentrance of the air into the pulverizer permits the reduction of the losses of load to a minimum and of economizing an important fraction of the motive power necessary 75 to the removal of the dust.

Claims:

1. A pulverizing apparatus, comprising a casing the bottom of which is provided with 80 a central opening, pulverizing devices acting against the internal periphery of the casing, a suction pipe communicating with the upper part of the casing, a blast pipe extending below the opening in the bottom of 85 the casing, a rotative distributor of air placed over the said opening and adapted to force the entering air from the center outwardly towards and into the grinding zone 90 at the periphery of the casing.

2. A pulverizing apparatus, comprising a casing, pulverizing devices in the casing, a suction pipe communicating with the upper part of the casing through a plurality of apertures, an adjustable regulating device 95 for each of the said apertures, a rotative distributor of air placed below the pulverizing devices, the pulverizing devices and air distributor being mounted on a common shaft, and a blast pipe opening into the 100 lower portion of the casing and below the rotative air distributing device.

3. A pulverizing apparatus, comprising a casing having on its internal periphery a circular base, rotatable pulverizing rollers 105 mounted in the casing and co-operating with the said circular base, means for feeding the material into the casing above the said rollers, a suction pipe communicating with the upper portion of the casing, a rotative air 110

distributing device mounted in the lower portion of the casing on the shaft of the pulverizing rollers and below the said rollers, scoops in the casing and adapted to rotate with the pulverizing rollers, and a blast pipe opening into the lower portion of the casing.

4. A pulverizing apparatus comprising a casing, a peripheral circular base and a horizontal partition centrally apertured, a suction pipe communicating with the upper part of the casing, a blast pipe communicating with the aperture of said partition, a shaft mounted in the casing, a turbine mounted on the shaft above the aperture of the partition, arms carried by the shaft above the turbine, pulverizing rollers carried by the shaft and cooperating with the said circular base, scoops rotating with the rollers between the turbine and casing, and

means for feeding the material into the casing above the pulverizing rollers.

5. In a pulverizing apparatus, the combination of a case the bottom of which is provided with a central opening, pulverizing means working against the internal periphery of the case, an air inlet pipe leading to the opening in the bottom of the case, and a rotary air distributor arranged above the said bottom opening and under the pulverizing means and adapted to drive the air entering at the middle towards the pulverizing area at the periphery of the case. 25

In testimony that I claim the foregoing as my invention I have signed my name in 30 presence of two subscribing witnesses.

JEAN AUBÉ.
